UNITED STATES PATENT OFFICE.

RICHARD G. PHEYSEY, OF ONTARIO, CALIFORNIA.

ELECTRICAL HEATING APPARATUS.

No. 888,923.

Specification of Letters Patent. Patented May 26, 1908.

Application filed August 22, 1907. Serial No. 389,651.

To all whom it may concern:

Be it known that I, RICHARD G. PHEYSEY, a subject of Great Britain, residing at Ontario, county of San Bernardino, and State of California, have invented a certain new and useful Improvement in Electrical Heating Apparatus, of which the following is a specification.

My invention relates to a new and useful improvement in electrical heating apparatus, and has for its object to simplify and cheapen the construction of various devices intended to be heated by electricity, such as laundry irons, stoves and the like, and a further object of my invention is to bring the heating coils in direct contact with the surface to be heated and surround said coils on all other sides with a heat non conducting material which will prevent the escape of heat in any direction except toward and to the surface to be heated.

A further object of my invention is to form the heating surface from sheet metal and to inclose the heating coils in a sheet metal shell, and a still further object of my invention when applied to a laundry iron is to provide a cast metal lid of sufficient weight to make up the proper weight of the iron.

With these ends in view, this invention consists in the details of construction and combination of elements hereinafter set forth and then specifically designated by the claims.

In order that those skilled in the art to which this invention appertains may understand how to make and use the same I will describe its construction in detail, referring by letter to the accompanying drawing forming a part of this specification, in which—

Figure 1 is a longitudinal section of my invention as embodied in a laundry iron. Fig. 2, a plan view of the sheet metal piece which holds the heaters in place. Fig. 3, an end elevation of the sheet metal holding piece. Fig. 4, a plan view of the sheet metal shell. Fig. 5, an end view of the sheet metal shell, a part being broken away and sectioned. Fig. 6, a side view of one of the cores of the heating coils. Fig. 7, an end view of the coil.

In carrying out my invention as here embodied, A represents a sheet metal shell which may be stamped or otherwise formed into the general shape of a laundry iron, and B is a sheet metal plate which fits upon the bottom of said iron and having the recess C

formed therein for the reception of the heating coils D, each coil having a core E of the shape shown in Fig. 6 so as to fit in the recess and hold the coils in place; the plate B has the ribs F formed therewith for partially inclosing the coils and also the bridge G for protecting the terminals H of said coils and likewise the plate as the raised portion I is formed at the opposite end to protect the terminals or connections between the coils, as will be readily understood.

J represents the heat non conducting material which is filled around the space occupied by the coils so as to prevent the escape of heat in any direction other than into the plate B thus avoiding the other parts of the iron from becoming heated and the heat being wasted by radiation, and K represents a cast metal lid of relatively considerable weight which is fitted into the shell and there secured by the screws L. This shell also has the holes M formed therein for the securement of the terminals H and the binding posts H'.

While I have here shown my invention as embodied in a laundry iron I do not wish to be limited to this use of the same as it is also especially adapted for electric stoves, ranges and the like or any device where it is desired to heat only one surface and prevent the heat from escaping through the other portions thereof.

Having thus fully described my invention, what I claim as new and useful, is—

1. As a new article of manufacture, an electric heating apparatus consisting of a sheet metal shell, a heater plate secured to said shell and having a recess formed therein for the reception of the heating coils, said coils being surrounded on the remaining sides by a heat non conducting material, and terminals secured in the shell, as specified.

2. In an electric heating apparatus, the combination of a sheet metal shell, a heater plate secured to said shell, a recess formed in said heater plate, coils located in said recess and in contact with said plate, off-set cores passing through the coils for holding them in place, heat non conducting material surrounding the coils except that portion thereof which is exposed to the heater plate, and a lid secured within the shell and upon the heat non conducting material, as and for the purpose set forth.

3. In an electric heating apparatus, the combination of a sheet metal shell, a heater

plate secured to said shell, a recess formed in said heater plate, coils located in said recess and in contact with said plate, off-set cores passing through the coils for holding them in place, heat non conducting material surrounding the coils except that portion thereof which is exposed to the heater plate, and terminals secured in the shell and electrically connected with the coils, as specified.

16 4. In a laundry iron, a sheet metal shell, a heater plate secured to said shell, ribs carried by said heater plate so as to form a recess, heating coils located within said recess, bridges also carried by the heater

plate for protecting the terminals of the 15 coils, heat non conducting material surrounding the coils except that portion thereof which comes in contact with the heater plate, and a cast metal lid secured within the shell and of sufficient weight to give the 20 proper weight to the iron, as specified.

In testimony whereof, I have hereunto affixed my signature in the presence of two subscribing witnesses.

RICHARD G. PHEYSEY.
